DOOR HANDLE WITH A LOCK-ACTUATING PUSH BUTTON OR SIMILAR ARTICLE

Giuliandra Meroni, Via Diaz 21, Nova Milanese,
Milan, Italy

Filed Feb. 4, 1974, Ser. No. 439,136

Claims priority, application Italy Sept. 21, 1973

Term of patent 14 years

Int. Cl. D8—06

U.S. Cl. D8—147

FIG. 1

FIG. 2

FIG. 3

FIG. 4

FIG. 1 is a perspective view of a door handle with a lock-actuating push button, or similar article, showing my new design;

FIG. 2 is a front end elevation thereof;

FIG. 3 is a side elevation thereof, rotated on its horizontal axis clockwise about 45° with respect to FIG. 2; and

FIG. 4 is a top plan view of the design shown in FIGS. 1 and 2.

I claim:

The ornamental design for a door handle with a lock-actuating push button or similar article, substantially as shown and described.
